UNITED STATES PATENT OFFICE.

IVAN C. BELL, OF DALLAS, TEXAS, ASSIGNOR TO THE GUIBERSON CORPORATION, OF DALLAS, TEXAS, A CORPORATION OF DELAWARE.

WELL SWAB.

Application filed June 13, 1927. Serial No. 198,353.

This invention relates to new and useful improvements in well swabs.

The object of the invention is to provide a well swab having an expandable flexible 5 swabbing element particularly designed and arranged so as to increase its wear resisting qualities when compressed and expanded under a load.

A particular object of the invention is to 10 provide a well swab comprising a plurality of helical flexible strips, each having one end held against movement, while the opposite ends of said strips are confined in a movable member whereby said strips tend to move 15 into close contact and compress under a load, thus more effectively resisting wear due to abrasion; but which, when travelling downward and free from a load, tend to separate and increase the fluent passage through the 20 body of the swab.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a view showing a portion of well 30 tubing in section and illustrating in full lines a swab constructed in accordance with the invention in its unloaded position, while in dotted lines a swab is shown in its loaded position,

Fig. 2 is a plan view of the swab,

Fig. 3 is an underside view of the same,

Fig. 4 is an elevation of the swab in its loaded or compressed position,

Fig. 5 is a vertical sectional view taken on the line 5—5 of Fig. 4,

Fig. 6 is a cross-sectional view taken on the line 6—6 of Fig. 4, and

Fig. 7 is a cross-sectional view taken on the line 7—7 of Fig. 4.

In the drawings the numeral 10 designates a mandrel which is reduced at its lower end and provided with an annular shoulder 11. A circular collar 12 is snugly fitted on the reduced end of the mandrel and secured 50 against the shoulder by nuts 13 screw-threaded on the lower end of said mandrel. The collar 12 is thus firmly secured against rotation. This collar is provided with upwardly flared annular trough 14.

Helically disposed rubber strips 15 have

their lower tapered ends 16 confined in the trough 12 by pins 17 passing through the walls of said collar. The strips are equally spaced so that their ends 16 rest between inlet ports 18 in the bottom of said collar, as is 60 shown in Figs. 3, 5 and 7.

The helical strips 15 are wound upon each other and have their upper ends 19 reduced and fitting in a downwardly flared trough 20 formed in the under side of a collar 21 free 65 to rotate around the mandrel. The ends 19 are secured by pins 22 and are spaced apart so that outlet ports 23 may be formed therebetween.

It will be noted that the collar 21 is larger 70 than the mandrel so as to leave a passage 24 there-between, as is shown in Figs. 2 and 5. This permits the fluid to exert a downward pressure through said passage and in the body of the swab. The strips have their 75 inner sides curved vertically, as is indicated at 25 in Figs. 5 and 6. This permits the fluid to accumulate in sufficient quantity within the expansible body of the swab and force the strips 15 laterally into engagement with 80 the inner wall of the tubing 26, as is indicated in dotted lines in Fig. 1.

It will be obvious that the collar 12 attached to the lower ends of the strips 15 being held against rotation, and the collar 21 being 85 free to rotate and secured to the upper ends of said strips, said strips will, upon rotation of the collar 21, either wind or unwind. It is apparent that when the collar 21 is forced downward and rotated in a counter-clockwise direction the strips will be wound and compressed, but upon an upward movement of the collar and rotation in a clockwise direction, the strips will tend to unwind. Thus, when the swab is forced downwardly in the 90 tubing 26 and is not loaded, the fluid entering through the ports 18 and passing upward between the ends 16 will tend to separate the strips, thus inducing the collar 21 to move upwardly and unwind said strips, as is 95 shown in full lines in Fig. 1, so that the fluid will escape through the ports 23.

When the mandrel 10 is pulled upwardly, the fluid above the swab will force the collar 21 downwardly, thus winding the strips 15, 105 compressing said strips and flowing through the passage 24 to fill the cavity in the body of the swab and thus expand the same, as is indicated in dotted lines in Fig. 1.

The strips are made of rubber or rubber 110

compound and the term "rubber" is used generically herein. It is well known that rubber, when expanded, is easily cut and does not resist abrasion, but when compressed, rubber is difficult to cut and its wear resisting qualities are greatly increased. It is pointed out that the expansion of the strips would be within a fraction of an inch on each side of the mandrel and the compression will in all 10 cases give the rubber strips such density as to negative the weakening of the rubber due to said expansion. The unwinding or elongating of the strips is very important, as it affords a much freer passage for the fluid 15 and permits the swab to be run down the tubing at a high rate of speed without detrimental effects.

Various changes in the size and shape of the different parts, as well as modifications 20 and alterations, may be made within the scope of the appended claims.

What I claim, is:

1. A well swab comprising helically disposed flexible strips mounted on a mandrel, 25 and means for causing a separation of said strips upon a down stroke of the swab to provide fluid passages between said strips around the mandrel.

2. A well swab comprising a support, a 30 body composed of flexible strips mounted on the support, non-rotatable means carried by the support for securing the strips at one end of the body, and rotatable means at the other end of the body attached to said strips, where- 35 by said strips are free to wind and unwind.

3. A well swab comprising a mandrel, a bottom collar secured to the mandrel, flexible

strips disposed about the mandrel and attached to the bottom collar, and a top collar rotatably mounted on the mandrel and to 40 which the upper ends of the strips are attached.

4. A well swab comprising, a mandrel, a bottom collar secured to the mandrel, flexible strips disposed about the mandrel and attached to the bottom collar, and a top collar 45 rotatably mounted on the mandrel and to which the upper ends of the strips are attached, the bottom collar having inlet ports and the top collar having outlet ports. 50

5. A well swab comprising a mandrel, a bottom collar secured to the mandrel against rotation, a top collar rotatable on the mandrel, and a plurality of rubber strips wound helically around the mandrel and their ends 55 secured in the collars in spaced order, said collars having fluid ports between the ends of said strips.

6. In a well swab, the combination of a mandrel having its lower end reduced and 60 provided with a shoulder, a bottom collar fastened on the mandrel against said shoulder and provided with spaced inlet ports, a top collar rotated and slidably on the mandrel and having spaced outlet ports, and a 65 plurality of rubber strips disposed helically around the mandrel between the collars with their ends secured to the collars between the ports thereof, the top collar having a fluid passage around the mandrel to the strips 70 which are spaced from said mandrel.

In testimony wherof I affix my signature.

IVAN C. BELL.
